UNITED STATES PATENT OFFICE.

EDWIN G. BUSSE, OF CHICAGO, ILLINOIS, ASSIGNOR TO CHICAGO RAILWAY EQUIPMENT COMPANY, OF CHICAGO, ILLINOIS, A CORPORATION OF ILLINOIS.

RAIL-SUPPORTING DEVICE.

1,221,832.

Specification of Letters Patent. Patented Apr. 10, 1917.

Application filed July 24, 1916. Serial No. 111,084.

To all whom it may concern:

Be it known that I, EDWIN G. BUSSE, a citizen of the United States, and a resident of Chicago, in the county of Cook and State 5 of Illinois, have invented certain new and useful Improvements in Rail-Supporting Devices, of which I do declare the following to be a full, clear, and exact description, reference being had to the accompanying drawing, forming a part of this specification.

The present invention has for its object to provide a rail supporting device or tie plate for supporting adjoining rails (such, for example, as a main line rail and a guard 15 rail) of a railway track. One of the main objects of the present invention is to provide a device which will enable adjoining rail sections of different sizes to be readily and firmly connected together and supported. 20 The present invention is particularly applicable for supporting the main line rail and adjacent guard rail. Heretofore it has been customary to use the same size or weight of rail both for the guard and main 25 rails. An objection to such construction is that in order to hold the rails in proper juxtaposition, it is necessary to cut away more or less of the inner flange of the guard rail,—an operation involving considerable 30 time, trouble and expense. By my present invention I am enabled to employ a guard rail materially smaller than the main line rail and to so support and connect it with respect to the main line rail that the cutting 35 of the inner flange of the guard rail is avoided. My invention also presents other features of advantage all of which will be hereinafter described, illustrated in the accompanying drawing and particularly pointed out in the claims at the end of this specification.

Figure 1 is a view in vertical section on line 1—1 of Fig. 3, through a main line and a guard rail with an intermediate filler block. Fig. 2 is a detail plan view of my improved supporting device. Fig. 3 is a plan view showing a portion of a track with my invention applied thereto.

A designates the main rail and B denotes the guard rail. It will be observed that the guard rail B is considerably smaller than the main rail A and between these rails is placed a filler block C that fits between the head and base flanges of the rails and is united 55 to the webs of the rails by means of a

through bolt D. The lower portion of the filler block C has its bottom reduced, as at e, to admit the inner base flange b of the guard rail B, a shoulder e of the filler block preferably abutting against the edge of the base flange b. As shown, a fishplate or washer E is arranged on the outside of the web of the guard rail B and against this washer bears the head of the through bolt D. Beneath the bases of the rails A and B extends the body portion of my improved plate F, the upper surface of which is formed with a flat portion to bear against the base of the main rail A and with a raised part F' on which rests the base of the rail B. This raised part F' is preferably formed by stamping or "bumping up" the plate F by suitable dies. The raised or arched portion F' is of less width than the body of the plate adjacent thereto, thus leaving the flat portions of the plate to bear against the tie and prevent the spreading or flattening of the arched portion F'. As shown, the plate F projects beyond the main and guard rails and at one end this plate F is provided with a shoulder adapted to engage the edge of the outer base flange a of the main rail A. This shoulder f is formed by stamping or "bumping up" metal from the plate F. The opposite end of the plate F is folded over upon itself, as clearly shown in Fig. 1, and this folded over portion is formed with a raised part to engage the guard rail B and resist the side thrust thereof. Preferably, the raised part of the plate F is stamped upward about its central portion to form a rail brace F², the inner and upper end of which extends to and bears beneath the head of the guard rail B. At each side of this brace portion F² the metal is bent inwardly and upwardly, as shown in Fig. 1; that is to say, the metal at each side of the raised part F² preferably extends for a short distance parallel with and rests directly upon the end portion of the plate F and then bends upwardly to form the shoulders f² adapted to engage the edge of the outer base flange b' of the guard rail B and is bent also inwardly, as at f³, to overlap the base flange b' of the guard rail. Suitable spike holes are formed at the opposite ends of the plate F, the spike holes adjacent the raised part F² passing through the reverted portions of the plate, as clearly shown in the drawing.

By reference to Fig. 1 of the drawing it

will be seen that when the parts are assembled as there shown, the main rail A will rest upon the lower portion of the plate F, while the guard rail B will rest upon and be supported by the raised portion F' of the plate, the outer base flange b' of the guard rail extending beneath the overlapping portions f³ and abutting against the shoulders f² on each side of the raised part F². The upper end of this raised part F² will extend beneath the outer portion of the head B of the guard rail. The filler block C will bear against the flanged head and base of the guard rail, the cut away portion c of the filler block admitting the inner flange b of the guard rail and permitting it to overlap the inner flange a' of the main rail A and the inner portion of this main rail will bear against the correspondingly shaped adjacent portion of the filler block.

It is obvious that the precise details of construction above set forth may be varied without departing from the spirit of the invention and that features of the invention 25 may be employed without its adoption as an entirety.

Having thus described my invention, what I claim as new and desire to secure by Letters Patent is:—

30 1. A brace plate for railway rails formed of a single piece of metal having a lower portion adapted to extend beneath and support one rail and having adjacent thereto a hollow arched portion rising from said plate and of less width than said plate, the crown of said arched portion forming a raised seat for a supplemental rail and being materially narrower than the base of said supplemental 35 rail, said brace plate having at the outer side of said arched portion a raised brace adapted to extend over the base flange and engage the upper part of said supplemental rail.

2. A brace plate for railway rails formed 45 of a single plate of metal and comprising a base having a struck up portion forming a raised seat for a supplemental rail and having adjacent thereto a flat portion forming a seat for the main rail, said metal plate being folded inwardly upon itself and bent upwardly at the end adjacent said raised seat to form a brace adapted to engage the base flange and upper portion of the supplemental rail.

50 3. A brace plate for railway rails formed of a single plate of metal and comprising a base having a struck up portion forming a raised seat for a supplemental rail and having adjacent thereto a flat portion forming a seat for the main rail, said metal plate being folded inwardly upon itself and bent upwardly at the end adjacent said raised seat to form a brace adapted to engage the base flange and upper portion of the supplemental rail and said plate being provided outside said main rail seat with an integral struck up part adapted to engage the base flange of the main rail.

55 4. The combination with a main and a supplemental rail of a brace plate having a lower portion adapted to extend beneath and support the main rail and having adjacent thereto a raised portion of less width 70 than the plate from which it is raised and adapted to extend beneath and support the base of the supplemental rail, said brace plate having also at the outer side of said raised portion a brace adapted to engage the base flange and upper portion of the supplemental rail, a filler block extending between the main and supplemental rails, and a bolt 75 passing through said main and supplemental rails and through said filler block and serving to unite said parts.

EDWIN G. BUSSE.
